UNITED STATES PATENT OFFICE.

HAROLD L. MYERS, OF MORRISTOWN, NEW JERSEY.

PAPER BOX.

1,310,765.

Specification of Letters Patent. Patented July 22, 1919.

Application filed November 9, 1918. Serial No. 261,766.

To all whom it may concern:

Be it known that I, HAROLD L. MYERS, a citizen of the United States, and a resident of Morristown, in the county of Morris and State of New Jersey, have invented certain new and useful Improvements in Paper Boxes, of which the following is a specification.

This invention relates to a paper box of novel construction in which goods may be shipped and also displayed to advantage upon a counter. The box is so constituted as to be readily foldable and to be self sustaining when set up, so that all pasting is dispensed with.

In the accompanying drawing:

Figure 1 is a perspective view of a paper box embodying my invention, showing it closed;

Fig. 2 a similar view of the box, partly broken away, showing it open and with one of the tongues disengaged;

Fig. 3, a vertical cross section on line 3—3 Fig. 4;

Fig. 4, a vertical longitudinal section on line 4—4 of Fig. 3;

Fig. 5, a horizontal section on line 5—5 Fig. 4; and

Fig. 6, a plan of the blank, drawn on a reduced scale.

The box is formed of a back 1, from each upright edge of which there extends forwardly at right angles, an inner member or side lining 2. Each lining 2 is overlaid by a covering or side proper 3, which is connected to member 2 at the top, and folds snugly against said member, so that each side of the box is doubled. From each side 3 extends inwardly at right angles, a side wing 4, the wings however being of such restricted length as to leave the main portion of the box front open, so that the goods are freely displayed between the same. The wings serve the dual function of holding the contents of the box in place, and of covering up and concealing the forward edges of linings 2.

From the lower edge of each lining 2 there extends inwardly, a horizontal flap 5, the two flaps being of such a length as to overlap at their free ends, and form conjointly a false bottom. The bottom proper 6 extends forwardly from the lower edge of back 1 and underlies false bottom 5. From the forward edge of bottom 6, extends up-

wardly, a doubled lower wing comprising an inner member or wing lining 7, and an outer member or wing covering 8, that is connected to the top of lining 7, and fits snugly against the same. The bottom wing 7, 8 constructed as described, serves the function of holding back the lower ends of the goods, though permitting their free display, and also of holding in position the side wings 4 by extending entirely across the same. From each end of covering 8, there extends backward along the lower ends of sides 3, a flap 9 provided with a tongue 10, which is adapted to be received by a slot 11, formed at the creased line 12, intermediate back 1 and lining 2. By passing the tongues into these slots, the doubled sides, the side wings, the double bottom, and also the doubled bottom wing are locked in position, so that the box is set up in a simple but reliable manner. From the upper edge of back 1 there extends a foldable top 13 provided in turn with a foldable flap 14. When the box is to be closed, the lower edge of this flap is tucked under lower wing lining, 7 to constitute a front (Fig. 1) while when the box is to be opened, the flap together with the top is thrown back (Fig. 2) and brought into engagement with a tab or support 15, stamped out of back 1, and bent slightly to the rear thereof.

In setting up the box from the blank (Fig. 6) proceed as follows: Turn forward inner sides 2 on lines 12; fold outer sides 3 against inner sides 2 on lines 16; fold wings 4 inwardly on lines 17; fold flaps 5 inwardly on lines 18; fold bottom 6 forward on line 19; double lower wing 7, 8 on line 20, and turn it upon line 21; turn flaps 9 back and insert their tongues 10 into the slits 11, which completes the operation.

The box constructed as described is well adapted to constitute when closed, a reliable shipping container which may be readily converted into an attractive display container by throwing back the top and front.

The box may be readily set up from the blank which may be stored and shipped flat as it requires no adhesive; it is of great strength, of neat appearance, and is so constituted that all of its exposed surfaces are formed from the same surface of the blank, so that all of the exposed surfaces may be covered with printed or similar matter at a single operation.

I claim:

1. A paper box comprising a back, a pair of sides, a pair of side wings, a bottom, a bottom wing, a foldable top, a foldable flap carried by the top, and adapted to be engaged by said bottom wing, and a support on the back that is likewise adapted to be engaged by said flap.
2. A paper box comprising a back, a pair of doubled sides, a pair of inwardly extending side wings, a doubled bottom, a doubled bottom wing extending upwardly from the doubled bottom, flaps carried by the doubled

bottom wing, and means for locking said flaps. 15

3. A paper box comprising a back, a pair of doubled sides, a pair of inwardly extending side wings, a doubled bottom, a doubled bottom wing extending upwardly from the doubled bottom across the side wings, flaps that extend rearwardly from the bottom wing along the doubled sides, means for locking said flaps, a foldable top carried by the back, and a foldable flap carried by said top.

HAROLD L. MYERS.
